RECORD DISPLAY RACK

Donald M. Levy, Los Angeles, Calif.
(6200 Franklin Ave., Apt. 504, Hollywood, Calif. 90028)

Filed Dec. 22, 1967, Ser. No. 9,888

Term of patent 7 years

U.S. Cl. D80—9
Int. Cl. D6—01

FIG. 1.

FIG. 2.

FIG. 3.

I claim:

The ornamental design for a record display rack, as shown.
